FASTENER PACKAGES

Harold T. Decot, Wenham, and Norman S. Derrah, Lynn, Mass., assignors to United Shoe Machinery Corporation, Flemington, N.J., a corporation of New Jersey
Filed Oct. 17, 1962, Ser. No. 231,223
17 Claims. (Cl. 1—56)

This invention relates to packaged articles and more particularly to packages of articles, such as fasteners and the like, which may be used with automatic and semi-automatic fastener inserting tools.

This application is a continuation-in-part of our co-pending application for United States Letters Patent Serial No. 148,252, filed October 27, 1961, and now abandoned.

Continuously increasing use is being made today of manual and power operated fastener driving tools to which fasteners, such as nails and the like, are supplied in prepackaged cartridges. One requirement of a package or cartridge is that the fasteners must be assembled or oriented therein in such manner that they may be driven directly from the package without the need for removal and/or additional orientation.

Another requirement of the package is that it be simple and foolproof to prevent the fastener becoming jammed or clogged in the tool, while at the same time it must be inexpensive to manufacture.

One of the objects of this invention is to provide an inexpensive package for articles, such as fasteners, wherein the articles are assembled and oriented so that they may be readily removed from the package one at a time by the normal operation of an instrument, such as a fastener inserting tool.

Another object of this invention is to provide a package of assembled and oriented fasteners from which fasteners may be driven one at a time without disturbing the arrangement of the remaining fasteners.

Another object of this invention is to provide a fastener package for use with driving tools which package is simple and sufficiently inexpensive to justify being discarded when the fasteners have been removed and which permits a saving in time in the operation of the tools.

In accordance with these objects and as a feature of this invention there is provided a package of articles, such as fasteners and the like, in which the package is preferably a unitary strip of sheet material with releasable means or members securing the articles individually to one side of the strip. The articles may be fasteners, such as nails, screws or the like, or any other article having a shank and at least one enlarged end. The releasable members securing the articles to the strip are generally arranged in a line and may include staples, rupturable stitches, frangible cement or adhesive, or the releasable means may be formed integrally with the strip as yieldable spring fingers which hold the articles individually so that one article at a time may be released from the strip while all of the others are retained in engagement with the strip. The articles are oriented and arranged relatively to each other and the strip is so constructed that when each article is driven in a direction generally lengthwise of its axis, engagement between its enlarged end and a predetermined portion of the strip produces a component of force normal to the strip to cause tension to be applied progressively to the individual strip portion or discrete member securing it to the strip until it ruptures or otherwise releases its holding power upon the article. No special removing elements are required other than a driver or other means for urging the article lengthwise of its axis.

The above and other features of the invention including various novel details of construction and combinations

2

of parts will now be more particularly described with reference to the accompanying drawings and pointed out in the claims. It will be understood that the particular packages shown embodying the invention are by way of illustration only and not as limitations of the invention. The principles and features of this invention may be employed in varied and numerous embodiments without departing from the scope of the invention.

In the drawings,

FIG. 1 is a side elevation of a fastener package made in accordance with the invention;

FIG. 2 is a side elevation of another fastener package made in accordance with the invention;

FIG. 3 is a sectional view taken along the line III—III on FIG. 1;

FIG. 4 is a sectional view taken along the line IV—IV on FIG. 1 and showing a fastener before its securing stitch has been ruptured;

FIG. 5 is a sectional view similar to FIG. 4 showing the fastener after its securing stitch has been ruptured;

FIG. 6 is a side elevation of another form of fastener package made in accordance with the invention;

FIG. 7 is a sectional view taken along the line VII—VII on FIG. 6;

FIGS. 8 and 9 are sectional views similar to FIG. 7 wherein the fastener is shown positioned in slightly different relationships to the holding strip;

FIG. 10 is a sectional view taken along the line X—X on FIG. 11;

FIG. 11 is a side elevation of another fastener package made in accordance with the invention;

FIG. 12 is a sectional view taken along the line XII—XII on FIG. 11;

FIG. 13 is a sectional view taken along the line XIII—XIII on FIG. 14;

FIG. 14 is a side elevation of another fastener package made in accordance with the invention;

FIG. 15 is a sectional view taken along the line XV—XV on FIG. 14;

FIG. 16 is a sectional view taken along the line XVI—XVI on FIG. 17;

FIG. 17 is a side elevation of a fastener package made in accordance with this invention wherein the holding means are an integral part of the strip itself;

FIG. 18 is a sectional view taken along the line XVIII—XVIII on FIG. 17;

FIG. 19 is a sectional view taken along the line XIX—XIX on FIG. 18;

FIG. 20 is another modification of the package similar to the FIG. 17 package; and,

FIG. 21 is a sectional view taken along the line XXI—XXI on FIG. 20.

Referring to FIGS. 1 and 3, the invention is illustrated embodied in a package of headed fasteners wherein the holding means are frangible stitches. The package comprises an elongated holding strip 2 of sheet material herein indicated as being fiber but which may be any firm substance, such as paper, cardboard, plastic, metal or the like. A plurality of fasteners, herein illustrated as common nails 4, are each secured by a single stitch 6 to the sheet 2. The stitches are part of a line 7 which extends lengthwise of the strip parallel to its upper and lower edges 8 and 10, respectively. The line 7 of stitches, or lines if it is so desired, as well as other holding means hereinafter to be described, may be curved as well as straight as shown. The strip also may be curved. The head 12 of each nail 4 is shown to be in engagement with the surface 14 of the strip 2 and at least a portion of its shank 16 also engages the surface 14. The stitches 6 are herein illustrated as chain stitches each of which engages the shank 16 of one nail, and when individually ruptured,

in the manner hereinafter to be disclosed, will not release the remaining stitches. Consequently, the removal of one fastener from the strip by rupturing its stitch will leave the remaining fasteners firmly secured to the strip. Additional holding power may be imparted to the line of stitches 6 by coating or impregnating the thread to cause it to adhere to the strip 2. Furthermore, a deposit of cement or other adhesive may be applied to the reverse side of the stitch line. The use of a strip made of plastic impregnated fiber also lends additional holding power to the line of stitches. 10

It will be noted in FIG. 1 that the axes A of the nails 4 are parallel to each other and at right angles to the major axis B of the strip 2. FIG. 2 shows an alternative manner of assembling the nails 4 in packaged form wherein their axes A are parallel and inclined at an angle to the major axis B of the strip. Their heads 12 are in contacting, overlapping relationship relative to each other. The angle upon which the axes may be most efficiently oriented relatively to the strip is taught in United States Letters Patent No. 3,031,670, granted May 1, 1962, in the name of Frederick S. Sillars. 15

Referring to FIGS. 4 and 5, which are sectional views of the strip shown in FIG. 1 and are also illustrative of the package shown in FIG. 2, the axes A of the nails are inclined at an acute angle with the surface 14 of the strip. Their heads 12 and at least a portion of their shanks 16 are in engagement with the surface. These packages are ideally suited for use in automatic or semiautomatic fastener machines of the type shown in United States Letters Patent No. 3,012,247, granted December 12, 1961, in the name of Frederick S. Sillars, wherein fasteners are individually removed from a package by a plunger which engages the heads one at a time and drives them substantially lengthwise of their axes into a work piece. As a nail is moved downwardly of the strip with its head 12 moving toward the stitch 6, it will be seen that the point 18, which is the junction between the head and the shank of the nail at the point most remote from the surface 14 of the strip, will move downwardly in a path substantially parallel with the surface 14 along the dotted line shown in FIG. 4. This maintains the upper portion of the shank 16 away from the surface 14. This movement progressively applies tension to the stitch until it ruptures, as shown in FIG. 5, and the fastener becomes released from the strip 2 with the remaining fasteners still in engagement therewith. 20

While the fasteners shown in the drawings are common nails, this invention is not limited to that type nor is it limited to nails of any kind but is equally applicable to elongated articles in general having a shank and an enlarged end. For example, screws may be secured to the holding strips and are capable of being removed therefrom in the same manner as the nails herein disclosed. Furthermore, a wedge shaped nail, i.e. one having no discernible head, such as a cut flooring nail or horseshoe nail, would operate to rupture the stitches in the same manner as a common or sinker nail. The articles must have shanks and at least one enlarged end. 30

FIGS. 6 through 9 illustrate a modified form of a strip 24. This strip of sheet material may be made of the same substances as the strips illustrated in FIGS. 1 to 5, but it includes a first area or surface 26 also known as the central area or surface and a second marginal area or camming surface 28 inclined at an acute angle to the surface 26. The non-planar strip 24, if desired, may also include a lower marginal surface 30 which, while it has no function in releasing the fastener from the strip, produces a strip of channel-like cross section which is more rigid than the flat strip 2 of FIGS. 1 to 5, or one having only the single marginal surface 28 in addition to the flat surface 26. Common nails 4 are shown secured to the strip 24 oriented as in FIG. 2, i.e. in engagement with each other and with their heads in overlapping relationship. They are herein illustrated as being secured to the strip by two lines of stitches 32, 34, the second line being op-

15
tional. Only a single stitch of each line holds each nail to the strip 24. FIGS. 6 and 7 show the heads 12 engaging the surface of the upper marginal camming area 28 while FIGS. 8 and 9 show alternative arrangements wherein the heads 12 initially are out of engagement with the camming surface 28. FIG. 8 shows the head below the upper edge 36 of the strip and FIG. 9 the head 12 above the upper edge 36. In each instance, however, the heads 12 are engageable with the surface of the inclined upper marginal surface 28 of the strip. 20

25
Nails are removed from the strip 24 in a manner similar to that in which they are removed from the strips shown in FIGS. 1 to 5. When the head 12 of a nail is urged toward the stitch 6 securing its shank, the head, either being initially in engagement with the camming surface 28 or engageable therewith upon movement, is urged or cammed outwardly by the surface 28, a component of force normal to the strip applying tension to the individual stitch 6 engaging its shank 16. Depending upon the tightness of the line of stitches, the stitch 6 will rupture either before the head reaches the central area 26 or shortly thereafter as tension further increases. The lower stitch, i.e., in the line 34 will rupture in the same manner as those shown in FIGS. 4 and 5.

30
FIGS. 10 through 12 illustrate a modified form of the strip shown in FIG. 6. The modified strip may be made of the same substance as in the strips hereinabove described and includes, as does the FIG. 6 strip, a marginal camming surface or area 28 inclined at an acute angle to a central area designated generally by the reference character 38 and the axes A of the assembled nails. This strip also if desired may include a lower marginal inclined surface 30 although it is not necessary to the invention.

35
In the central area or surface of the FIG. 10 strip there are formed by die rolling, stamping, molding or the like, a line of ridges 40, each ridge being separated by a valley 42 of approximately the same diameter as the shank 16 of the nail to be secured to the strip. The valleys are oriented parallel to each other and on an angle with respect to the major axis B of the strip as taught in the above-identified Sillars Patent No. 3,031,670. The valleys 42 receive the shanks 16 of the nails and adjacent ridges, i.e. a pair of ridges assist the lines 32 and 34 of stitches 6 in maintaining the nails in oriented, shingled and parallel relationship. The ridges and valleys 40, 42 also offer additional rigidity to the strip in a direction transversely of the major axis B, i.e., lengthwise of the strip as well as parallel to the axis or widthwise of the strip. The presence of the ridges and valleys 40, 42 also will assist in camming the fasteners outwardly of the strip as their heads 12 move over the ridges, further to insure rupture of the stitches 6 forming the lower line 34.

40
50
55
FIGS. 13 through 15 illustrate still another modification of the fastener strip which includes in the central area 26 or first surface, a single line 7 of individual stitches 6 securing fasteners, such as nails, to the strip. This strip will be seen to include two parallel lines 41 and 43 of ridges 44 and valleys 46 located on opposite sides of the surface 26. The ridges 41 and 43 are formed as a continuation of upper and lower inclined surfaces or areas 48 and 50, respectively, and are located inwardly of their edges. The areas 48 and 50 will be seen to be slightly longer than the corresponding surfaces 28 and 30 in the FIGS. 6 and 11 modifications. The surface 48 is the camming surface equivalent to the surface 28 of the FIG. 6 and the FIG. 11 modifications. Fasteners, such as nails, are maintained in the valleys 46 inclined and oriented as shown in FIG. 14 and requiring only the single stitch line 7 through the central portion 26 of the strip.

60
65
70
75
In neither the FIG. 11 nor the FIG. 14 modification is it necessary for the nail shank to be assembled in initial engagement with the flat portions of the central

areas 38 and 26 of the respective strips. Furthermore, as illustrated in FIGS. 8 to 10, the heads 12 of the fasteners may either be initially in engagement with or be engageable with the camming surfaces 28 and 48. Fasteners oriented as such are removed from the FIG. 11 and FIG. 14 strips in the same manner as they are removed from the FIG. 6 strip.

While all of the foregoing modifications are illustrative examples of fastener holding means in the form of one or more lines of stitches with the fastener being held by one stitch of the line it forms a part of, in accordance with this invention the holding means may be any equivalent releasable means, for example, a line of staples, one staple of a given line holding the fastener to the strip. Upon being cammed outwardly of the strip, the staples' legs would pull out of the strip or the staple would rupture. Another equivalent of either the stitches or the staples is either a continuous or interrupted line or frangible cement or adhesive by which each nail of the FIG. 14 modification, for example, would be secured to the central area 26. The frangible adhesive or cement would pull away from the area 26 of the strip upon the application of sufficient force or would break out around the nail. The individual adhesive dabs could be independent of each other or merge into one another forming a continuous line of adhesive. It is also contemplated that the adhesive could be applied over the entire portion of the nail shank overlying the strip in the valleys 46, as well as, in the central area 26. Similarly, in the modification shown in FIGS. 6 and 11 the nails may be secured by more than one line of dabs of adhesive or continuous lines of adhesive. Furthermore, the adhesive may engage a length of the shank of the nails so as to secure a longer portion of the nail shank to either the valleys 42 and/or the flat portions of the areas 38 and 26 of the FIGS. 11 and 6 modifications, respectively.

FIGS. 16 through 18 illustrate one, and FIGS. 19 through 21 illustrate another modification wherein the holding means are not necessarily frangible nor will they separate from the strip but in each instance are integral yieldable portions of the strip. In the FIG. 17 modification the shanks 16 of common nails 4 lie within grooves 52 similar to the grooves 42 of the FIG. 11 modification of the strip. However, the strip is made from a relatively flexible plastic material. Each nail is held within the valleys or grooves 52 by a pair of fingers 54 arranged in a line 55. The fingers 54 are formed by indenting or otherwise causing the plastic material of the ridges 56 between the grooves to expand laterally overlying portions of the grooves 52. For example, a heated roll which is moved under pressure along the axis B of the strip in engagement with the ridges 56 will melt or soften the ridges to form the fingers 54, it being seen in FIG. 17 that the fingers are depressed slightly below the upper surface of the ridges 56.

The FIG. 17 strip is also provided with a camming surface 28 as are the FIGS. 6, 11 and 14 modifications, the lower marginal deflected leg 58 of the strip being optional and being used primarily to increase rigidity of the strip and prevent bending transversely of its axis. The nails are removed from the strip in the same manner as in the prior modifications wherein their heads or enlarged portions are cammed outwardly by the surface 28, whereupon tension is applied to the yieldable fingers 56 which will then release the nails. The FIG. 17 fastener strip has the obvious advantage that since the holding means are not destroyed, the strips may be reused after the nails have been driven from it.

FIGS. 19 through 21 illustrate still another reusable form of strip having yieldable means for holding fasteners or other articles to the strip. Each article, again illustrated as a nail, lies within one of a plurality of parallel grooves 60 arranged in a line through the central portion of the strip. Each groove is covered by a pair of yieldable, elongated, curved fingers, the pair forming

what might be considered a roof 62. The holding means thus resemble a series of parallel tunnels in the surface of the strip, the roofs 62 being curved upwardly from the grooves 60 and each having a slit 64 extending lengthwise of the holding grooves. The holding members may also be considered as releasable pockets or fingers. It will be noted that the strip, which is also formed of a yieldable plastic or the like, has a camming surface 28 whereby when the nail is urged downwardly, its head 12, as in the similar modifications, engages the surface 28 causing the shank 16 to be urged outwardly against the inner surface of the roof 62 whereupon the fingers 61 will open along the slits 64 permitting the nail to move laterally out of the pockets. The FIG. 20 modification may also be refilled with fasteners as may the FIG. 17 modification.

It will be seen from the numerous illustrations that a package of articles made in accordance with this invention includes a strip of packaging material to which a plurality of articles are secured by frangible or releasable means including members, such as, staples, stitches, frangible cement, or releasable fingers or pockets. The articles may be oriented in various ways relative to the strip but an enlarged portion, such as the head or broad end of a tapered nail, must be in engagement or become engageable with at least a portion of the strip which acts as a camming surface in order to pull out the holding staple, rupture a stitch, break the adhesive bond or yieldably urge the article out of a groove or pocket in which it is held. The axes of the article's shanks are initially inclined at acute angles at least with a portion of a surface of the strip, i.e., the respective camming surfaces. Note also that in all modifications the nail heads or the equivalent enlarged end part of the articles if it is a cut flooring nail or horseshoe nail for example, are initially spaced from the stitch or other holding member or strip portion which secures its shank to the strip, and at least a portion of the shank engages the strip initially in every modification. In other words, more than just the head of a fastener must be initially in engagement with the strip.

Having thus described our invention, what we claim as new and desire to secure by Letters Patent of the United States is:

1. A package of articles such as fasteners and the like, each article having a shank and an enlarged end, said package comprising a strip of sheet material, at least one line of rupturable stitches securing the articles to the strip, each article being secured by a single stitch of the line of which it is a part, said strip including means cooperative with the enlarged end of each article to exert a component of force normal to the strip when the article is moved lengthwise of itself thereby to release the article from the stitch securing it to the sheet.

2. A package of articles such as fasteners and the like, each article having a shank and an enlarged end, said package comprising a strip of sheet material, at least one line of releasable plastic fingers securing the articles to the strip, each article being secured by a single pair of releasable fingers of the line of which they are a part, said strip including means cooperative with the enlarged end of each article to exert a component of force normal to the strip when the article is moved lengthwise of itself thereby to release the article from the plastic fingers securing it to the strip.

3. A package of articles such as fasteners and the like, each article having a shank and an enlarged end providing a head angularly projecting from the shank, said package comprising only a single strip of sheet material having at least one line of releasable members removably securing the articles to a side of the strip with the axis of each article forming an acute angle with at least a portion of the side surface of the strip, each article having spaced contacts with the strip surface at its head and its shank, each article being secured by a single member of the line

of which it is a part engaging its shank at a location spaced from its enlarged head end.

4. A package of articles such as fasteners and the like, each article having a shank and an enlarged end, said package comprising a strip of sheet material and at least one line of rupturable stitches removably securing the articles to the strip with the axis of each article forming an acute angle with at least a portion of the surface of the strip, each article being secured by a single stitch of the line of which it is a part engaging its shank at a location spaced from its enlarged end. 10

5. A package of articles such as fasteners and the like, each article having a shank and an enlarged end, said package comprising a strip of plastic material and at least one line of releasable plastic fingers removably securing the articles to the strip with the axis of each article forming an acute angle with at least a portion of the surface of the strip, each article being secured by a single pair of fingers of the line of which they are a part, said fingers engaging the shank of the article at a location 15 spaced from its enlarged end.

6. A package of articles such as fasteners and the like, each article having a shank and an enlarged end providing a head projecting laterally from the shank, the package comprising a unitary strip of sheet material having at least one line of releasable members removably securing the articles to one side of the strip, a single securing member of the line of which it is a part engaging the shank of each article, each article being oriented with the axis of its shank at an acute angle with at least a portion of the surface of said one side of the strip and with its enlarged end engageable with said portion and spaced from said securing member before said member releases the article, there being a triangular opening defined by said side of the strip and that portion of the shank of each article adjacent to its head, whereby when the enlarged end of the article is moved toward the securing member engagement between the enlarged end and said surface causes tension to be applied progressively to the securing member until it releases the article. 25

7. A package of articles such as fasteners and the like, each article having a shank and an enlarged end, the package comprising a strip of sheet material and at least one line of rupturable stitches removably securing the articles to the strip, a single stitch of the line of which it is a part engaging the shank of each article, each article being oriented with the axis of its shank at an acute angle with at least a portion of the surface of the strip and with its enlarged end engageable with said portion and spaced from said stitch before the stitch releases the article, whereby when the enlarged end of the article is moved toward the stitch engagement between the enlarged end and said surface causes tension to be applied progressively to the stitch until it ruptures and releases the article. 35

8. A package of articles such as fasteners and the like, each article having a shank and an enlarged end, the package comprising a strip of plastic material and at least one line of plastic fingers removably securing the articles to the strip, a single pair of fingers of the line which it is a part engaging the shank of each article, each article being oriented with the axis of its shank at an acute angle with at least a portion of the surface of the strip and with its enlarged end engageable with said portion and spaced from said pair of fingers before said fingers release the article, whereby when the enlarged end of the article is moved toward the pair of fingers engagement between the enlarged end and said surface causes the article to apply tension progressively to the fingers until they release the article. 40

9. A package of articles such as fasteners and the like, each article having a shank and an enlarged end, the package comprising a strip of sheet material having a first area and a second marginal area inclined at an acute angle thereto, releasable members in the first area

securing the shanks of the articles to the strip with at least a portion of the shanks overlying said marginal area and with the enlarged ends spaced from said releasable securing members and engageable with said marginal area. 5

10. A package of articles such as fasteners and the like, each article having a shank and an enlarged end, the package comprising a strip of sheet material having a first area and a second marginal area inclined at an acute angle thereto, rupturable stitches in the first area securing the shanks of the articles to the strip with at least a portion of the shanks overlying said marginal area and with the enlarged ends spaced from said stitches and engageable with said marginal area. 10

11. A package of articles such as fasteners and the like, each article having a shank and an enlarged end, the package comprising a strip of plastic material having a first area and a second marginal area inclined at an acute angle thereto, releasable plastic fingers in said first area securing the shanks of the articles to said strip with at least a portion of the shanks overlying said marginal area and with the enlarged ends spaced from said releasable plastic fingers and engageable with said marginal area. 15

12. A package of articles such as fasteners and the like, each article having a shank and an enlarged end, the package comprising a strip of sheet material having a first area and a second marginal area inclined at an acute angle thereto, releasable members in the first area securing the shanks of the articles to the strip with at least a portion of the shanks overlying said marginal area and with the enlarged ends spaced from said releasable securing members and engageable with said marginal area, and at least one line of spaced ridges in said first area with the shanks of the articles lying between adjacent individual ridges of the line of which they are a part. 20

13. A package of articles such as fasteners and the like, each article having a shank and an enlarged end, the package comprising a strip of sheet material having a first area and a second marginal area inclined at an acute angle thereto, releasable members in the first area securing the shanks of the articles to the strip with at least a portion of the shanks overlying said marginal area and with the enlarged ends spaced from said releasable securing members and engageable with said marginal area, said first area including at least one line of parallel grooves with the shanks of each article lying in a single groove of the line of which it is a part. 25

14. A package of articles such as fasteners and the like, each article having a shank and an enlarged end, the package comprising a strip of sheet material having a central area and two marginal areas inclined at acute angles to the central area and diverging away from each other, two lines of spaced parallel ridges extending lengthwise of the strip inwardly of the outer edges of said marginal inclined areas, releasable members in the central area between said lines of ridges securing the shanks of the articles to said strip with the shanks lying between adjacent individual ridges of each line and at least a portion of the shanks overlying one marginal inclined area with the enlarged ends engageable therewith and spaced from said releasable securing members. 30

15. A package of articles such as fasteners and the like, each article having a shank and an enlarged end, the package comprising a strip of sheet material having a central area and two marginal areas inclined at acute angles to the central area and diverging away from each other, two lines of parallel grooves extending lengthwise of the strip inwardly of the outer edges of the marginal inclined areas, releasable members in the central area between said lines of grooves securing the shanks of the articles to said strip with the shank of each article lying in a single groove of each line and at least a portion of the shank overlying one marginal inclined area and with

the enlarged end engageable therewith and spaced from said releasable securing members.

16. A package of articles such as fasteners and the like, each article having a shank and an enlarged end, the package comprising a strip of sheet material having a central area and two marginal areas inclined at acute angles to the central area and diverging away from each other, two lines of parallel grooves extending lengthwise of the strip and located inwardly of the outer edges of the marginal inclined areas, a line of rupturable stitches in the central area between said lines of grooves securing the shanks of the articles to said strip with each article lying between adjacent individual ridges of each line and secured by a single stitch with at least a portion of the shanks overlying one marginal inclined area with the enlarged ends engageable therewith and spaced from said line of stitches.

17. A package of articles such as fasteners and the like, each article having a shank and an enlarged end,

the package comprising a strip of sheet material having a central area and two marginal areas inclined at acute angles to the central area and diverging away from each other, two lines of spaced parallel ridges extending lengthwise of the strip and located inwardly of the outer edges of said marginal areas, a line of rupturable stitches in the central area between said lines of ridges securing the shanks of the articles to said strip with each article lying between adjacent individual ridges of each line and secured by a single stitch and with at least a portion of the shanks overlying one marginal inclined area with the enlarged ends engageable therewith and spaced from said line of stitches.
